United States Patent Office

Des. 193,914
Patented Oct. 23, 1962

193,914

PROJECTOR

Josef Bönisch, Dresden-Weisser Hirsch, Germany, assign-
or to VEB Kamera- und Kinowerke Dresden, Dresden,
Germany

Filed Nov. 25, 1960, Ser. No. 62,980

Term of patent 14 years

(Cl. D61—1)

FIG. 1 is a front perspective view of a projector showing my new design;

FIG. 2 is a front perspective view thereof, from a second angle;

FIG. 3 is a front perspective view of the opposite side thereof; and

FIG. 4 is a side elevational view thereof.

I claim:

The ornamental design for a projector, as shown.
